(57) **CLAIM**

The ornamental design for a boat shaped pool for spa, as shown and described.

DESCRIPTION

FIG. 1 is an upper perspective view of a boat shaped pool for spa;

FIG. 2 is a front view thereof;

FIG. 3 is a rear view thereof;

FIG. 4 is a left side thereof;

FIG. 5 is a right side view thereof;

FIG. 6 is a top view; and,

FIG. 7 is a bottom view thereof.

The broken lines shown in the figures represent portions of the boat shaped pool for spa that form no part of the claimed design.
